UNITED STATES PATENT OFFICE.

JOSEPH M. SHIVELY, OF ALFRED, KANSAS, ASSIGNOR TO DEERING HARVESTER COMPANY, OF CHICAGO, ILLINOIS.

CORN-SHOCKER.

SPECIFICATION forming part of Letters Patent No. 681,517, dated August 27, 1901.

Application filed February 6, 1901. Serial No. 46,321. (No model.)

To all whom it may concern:

Be it known that I, JOSEPH M. SHIVELY, a citizen of the United States, residing at Alfred, in the county of Douglas and State of Kansas, 5 have invented certain new and useful Improvements in Corn-Shockers; and I do hereby declare the following to be a full, clear, and exact description of the invention, such as will enable others skilled in the art to which 10 it appertains to make and use the same, reference being had to the accompanying drawings, forming a part of this specification.

My invention relates to devices for lifting the shock formed upon the machine and 15 depositing it upon the ground. It is an improvement upon the machine patented to me May 5, 1896, No. 559,754; and it consists in means for rendering the shock-lifting core semi-automatic in its action in dropping the 20 shock.

In the drawings, Figure 1 is a perspective view of the core around which the shock is formed, its radial arms and spreaders, and means for operating them, all as in position 25 while sustaining the shock when forming there around. Fig. 2 shows the same parts, but with the spreaders and radial arms closed to the position they occupy when being drawn from the shock. Fig. 3 is a plan view of the 30 tripping-latch. Fig. 4 is a side elevation of the parts shown in Fig. 3. Fig. 5 is a longitudinal sectional view of the devices for holding the radial projecting arms in position. Fig. 6 is a plan view of parts shown in Fig. 35 5. Fig. 7 is a side elevation of the means provided for locking the telescoping pipes together during withdrawal of the core from the shock. Fig. 8 is a side elevation of parts shown in Fig. 7 with one of the bars *h* removed, but which has been turned through 40 an angle of ninety degrees about a vertical axis; and Fig. 9 is a perspective view of a portion of the revolving table, showing the square stud which supports the shock-forming post in its vertical position and causes 45 the same to revolve.

A is a square pipe having a disk *a* at its lower end. Upon the rotary table *B*, as that shown in my previous patent above referred 50 to, at its center I secure to the rotary table

the square stud *b*, which fits within the lower end of the square pipe *A*.

C is a square pipe outside the square pipe *A*, in which the square pipe *C* is adapted to move longitudinally.

The lifting device from the shock when formed consists of the crane *D*, suitably supported upon the main frame of the machine having the pulleys *d* and *d'* and the rope *d* and a suitable windlass to pull the 60 rope. The pulley *d* is secured to the crane and the pulley *d'* connected to the pipe *A* by means of the swivel *a'*. The spreaders *E* are pivoted at *e* to a collar on the pipe *C*. When the ropes are drawn, by means of 65 windlass or otherwise, the movement of the pipe *A*, having the disk *a* through the pipe *C*, causes the disk *a* to press the spreaders outward. It is preferable that they be moved substantially equally, and hence I provide 70 the chains *a* and link them together.

So far as now described this construction is found in the patent above referred to and need not be dwelt upon.

Upon the pipe *C* is clamped the sleeve *F*. 75 It is constructed as shown in Figs. 5 and 6, its size being such as to pass freely onto the pipe *C*, but by means of the pinch-bolt *f* may be secured to the pipe at any desired place. This is for varying the vertical position of the 80 arms to conform them to corn of different heights.

f'; *f*², *f*³, and *f*⁴ are arms pivoted to the sleeve *F* at *f*⁵. Each arm is provided with an upturned end *f*⁶ near its pivot, as shown 85 in Fig. 5.

Adapted to slide freely for a limited distance on the sleeve *F* is the collar *G*, having the downwardly-projecting peripheral flange *g*. By reference to Fig. 5 it will be readily 90 understood that if the collar *G* is raised the flange at once sets the upturned ends *f*⁶ of the arms free and the arms are permitted to fall to the position shown by dotted lines.

The means for lifting the collar *G* will be 95 understood by reference to Fig. 1. Upon the opposite sides of the collar are the loops *H* and *H*, and extending upwardly outside of the pipe *C* are the bars *h* and *h*, and connecting the said bars at the top is the plate *h'*. 100

Upon the two bars are the stops h^2 and h^3 . Surrounding the pipe C and the parts last described is the ring I, and extending upwardly from it is the bar I', having the notches i , i' , i^2 , 5 and i^3 . This bar is sustained at its upper end by mechanism soon to be described.

Extending from the case of the pulley d' is a slotted link d^2 .

In order that the core of my shocking-machine may rotate while the shock is accumulating without twisting the ropes d^2 , the swivel a' , before mentioned, is provided, and in order that the core may rotate without carrying the bar I' with it the said core is free 15 to turn in the ring I. Upon the top of the crane-arm D is the latch for the bar I'. This part is shown in detail in Figs. 3 and 4. A slotted sleeve K is pivoted at k and k' between the arms k^2 and k^3 , which arms are 20 formed by bending the part k^4 , as shown in Fig. 3. The part last mentioned is riveted to the upper end of the crane D. Within this slotted sleeve is pivoted the latch L, which is adapted to engage any of the notches 25 i , i' , i^2 , or i^3 of the bar I'. As the shock when suspended and being moved from the shocking-table is likely to swing from side to side, the sleeve K is pivoted, as before stated, and in order that the bar I' may not cramp within 30 the slot in the sleeve the slot is made sufficiently long to permit of considerable vibration. The upper portion of the crane D is constructed of bars of iron D^2 , preferably 35 formed, as shown in Fig. 1, to give place for securing of the end of the rope. This forms a support for the pulley d and place for attaching the locking device that engages the bar I'. The spring-latch L, pivoted within the sleeve K, has secured to it the rope l , 40 which leads downward along the arm D to within convenient reach of the operator.

The operation of my device is as follows: With the arms f' , f^2 , f^3 , and f^4 raised, as shown in Fig. 1, and the shock formed, the 45 rope d^2 is pulled by windlass or otherwise, and as the pipe A, to which the rope is indirectly connected, moves upward the disk a forces the spreaders E to the position shown. The core and shock surrounding it as a whole 50 is then lifted to any desired height to draw the pipe A from the square stud b , which projects upward from the rotary shocking-table. The crane is then swung to such a position that the shock may be dropped to the ground 55 sufficiently far from the standing corn to permit the machine to pass upon another round, as in my patent above referred to. As the shock-forming device is raised the bar I' passes upwardly through the sleeve K, so that 60 one of the notches i , i' , i^2 , or i^3 is engaged by the latch L. When the shock is to be dropped, the rope d^2 is set free. The weight of the core and the shock surrounding it is then sustained by the bar I', the ring I of which comes in contact with the plate h' and draws the collar G, 65 through the intermediary of the bars h and the loop H, upward relative to the sleeve F,

and thus disengages the arms f' , f^2 , f^3 , and f^4 and permits them to fall. Not only this, the weight of the entire apparatus being sustained by the bar I' the pipe A is free to move downward by its weight or by the pressure of the spring e' , and thus permit the spreaders E to collapse. The action of the parts thus far is to permit the shock to be dropped to 70 the ground. The core has yet to be drawn upward through the top of the shock. This is done by pulling upon the rope d^2 until the core is raised sufficiently high. It is plain, however, that if the pipe A were free to move 80 upward relative to the other parts the disk a would force the spreaders and prevent the withdrawing of the core from the shock. Upon the pipe C is the spring-latch M, with a pin m , adapted to enter the hole m' in the pipe A. When the latter pipe is at its lowest position, with the two pipes locked together, it will be seen that the stress is reapplied to the rope d^2 . The spiders are not moved. The core having been fully removed from the 85 shock is swung to its position over the shock-forming table and lowered. The spring-latch L is disengaged from the notches i , i' , i^2 , or i^3 by pulling upon the rope l . The pipe A is then placed in position on the square stud b 90 of the rotary table and the latch M is withdrawn, so as to leave the pipes C and A free to move relatively to each other in the next operation of removing the shock. The arms f' , f^2 , f^3 , and f^4 are raised and the collar G 95 permitted to engage them and hold them in the position shown.

Having thus described my invention, what I claim as new, and desire to secure by Letters Patent, is—

103

1. In a corn-shocking machine, the combination with a shock-forming post having pivoted arms, a trigger adapted to engage said arms and to lock them in radial position relative to said post and by longitudinal movement of same, relative to said post, to unlock said arms, and a shock-lifting hoist, of a trigger-pull consisting of the notched bar I' adapted to engage said trigger, a guide upon the arm of said hoist, said notched bar passing upward through said guide, and a catch upon said guide whereby the notched bar may be arrested from downward movement when the hoisting device is permitted to lower the shock-forming post, substantially as described.

110

2. In a corn-shocking machine, the combination with a shock-forming post having pivoted arms, a trigger adapted to engage said arms and to lock them in radial position relative to said post and by longitudinal movement of same, relative to said post, to unlock said arms, and a shock-lifting hoist, of a trigger-pull consisting of the notched bar I' adapted to engage said trigger, a guide upon the arm of said hoist, said notched bar passing upward through said guide, and a catch upon said guide whereby the notched bar may be arrested from downward movement when 115

120

125

130

135

the hoisting device is permitted to lower the shock-forming post, means for moving said catch out of engagement with said notched bar to permit the same to move downward 5 when the shock-forming post is lowered to its position on the table, substantially as described.

3. In a corn-shocking machine, the combination with a shock-forming post having pivoted arms, a trigger adapted to engage said arms and to lock them in radial position relative to said post and by longitudinal movement of same, relative to said post, to unlock said arms, and a shock-lifting device connected to the top of said post by a swivel, of a catch on said shock-lifting device and a trigger-pull extending from said catch downward and surrounding said trigger, whereby the shock-forming post is free to rotate while 15 forming the shock without affecting the position of said trigger-pull relative to said lifting device, substantially as described.

4. In a corn-shocking machine, the combi-

nation with a shock-forming post having pivoted arms, a trigger adapted to engage said arms and to lock them in radial position relative to said post and by longitudinal movement of same, relative to said post, to unlock said arms, and a shock-lifting device, of a trigger-pull adapted to move a limited distance longitudinally relative to said trigger and to engage therewith, whereby the trigger is permitted to move downward with the shock-forming post for a little distance and the said trigger then arrested by engagement 35 with the said trigger-pull, whereby the momentum of the descending post and shock is instrumental in setting the arms free, substantially as described.

In testimony whereof I affix my signature 40 in the presence of two witnesses.

JOSEPH M. SHIVELY.
